Robert K. Andre, Miami, Fla.

Application February 11, 1959, Serial No. 54,559

Term of patent 7 years

(Cl. D56—4)

Figure 1 is a side perspective view of a radio showing my new design;

Figure 2 is a front elevational view;

Figure 3 is a side elevational view with the body portion broken away for purpose of illustration of the radio device; and

Figure 4 is a slightly enlarged detail in perspective of the projection shown in the left of Figure 3.

The appearance of the base when viewed from the side opposite to that shown in Figs. 1 and 3 is substantially identical thereto.

I claim:

The ornamental design for a radio, as shown and described.
